UNITED STATES PATENT OFFICE

ROBERT B. HESSON, OF MIDDLESEX BOROUGH, NEW JERSEY, ASSIGNOR TO RESEARCH CORPORATION, OF NEW YORK, N. Y., A CORPORATION OF NEW YORK

INSULATOR

Application filed May 17, 1938. Serial No. 278,478.

This invention relates to improvements in insulators, and more particularly to insulators which, due to their construction or place of use, are subject to damage or destruction 5 arising from deposits thereon of conductive material.

In electrical precipitators for the removal of tar and light oils from gas the problem of maintaining the insulators in working 10 condition has caused considerable trouble, due to the fact that deposits of tar, oil, water and the like on the insulators results in a conductive surface between the discharge electrode system and the ground. The insulators are damaged by burning or may be 15 destroyed by the flash-over or arcing conduction which takes place when the conductive deposit is formed. As the insulators provide the mechanical support for the discharge 20 electrode system the replacement of a broken or damaged insulator requires considerable time as it is usually necessary to readjust the discharge electrodes with respect to the collecting electrodes. The actual cost 25 of the insulators is also a material item in the operating expenses.

An object of the invention is to provide an insulator which is enclosed within a substantially air-tight housing, the housing being 30 formed, in part at least, of insulating material.

A further object of this invention is to provide an insulator construction, including a relatively inexpensive and easily renewable 35 insulating surface which protects the main insulator from deposits of conductive material.

A further object is to provide an auxiliary insulating surface in parallel with and forming 40 a protective housing for the main insulator.

More specifically, an object of the invention is to provide an electrical precipitator in which the insulators which carry the discharge 45 electrodes are protected by an auxiliary insulating surface formed of relatively inexpensive material, thereby preventing the deposition of conductive material upon the insulators.

These and other objects of the invention

will be apparent from the following specification, when taken with the accompanying drawings, in which

Fig. 1 is a fragmentary side view, partially in section, through a portion of an electrical 55 precipitator.

Fig. 2 is a vertical section through a pedestal insulator embodying the invention,

Fig. 3 is a side elevation of a strain insulator provided with a protective covering, 60 and

Fig. 4 is a sectional view illustrating a further modification of the invention.

In the drawings the numeral 1 indicates a portion of the treater chamber of an electrical precipitator having discharge electrodes 2 and collecting electrodes 3 mounted therein. The discharge electrodes 2 are carried by a beam 4 which extends through the wall of the treater chamber and into the insulator compartment 5. The beam 4 is supported by the insulator 6 which is in turn supported by the bottom wall 5' of insulator compartment 5 which is part of the grounded structure of the precipitator. A hollow insulator 6 serves to separate this grounded part of the precipitator from the high voltage frame work supporting the discharge electrodes and the voltage drop along its surface from top to bottom is the voltage, above ground, which is impressed on the discharge electrode system. The beam 4 is connected to a high voltage current supply (not shown) by a conductor 7 which extends through the insulator and is insulated from the bottom wall 5' of the insulator compartment by an insulating bushing 6'.

The insulator chamber 5 is provided with a jacket 8 of heat insulating material, and a steam pipe 9 is provided for heating the insulator chamber. The outer wall of the chamber 5 is provided with a man-hole having a cover plate 10 which permits access to the interior of the chamber.

By thus heating the space within the insulator chamber the deposition of moisture, oil and tar may be reduced or substantially eliminated. To prevent damage to the insulator through the inadvertent stoppage of the steam supply the insulator 6 is provided with

a substantially air-tight housing or cover which is formed, in part at least, of insulating material, since the cover is subjected to the same potential difference as the insulator. As shown in Fig. 1, the usual flanged hood 11 is provided with a second flange 12 which is positioned within and extends below the outer rim of the hood. A cylindrical shell 13 of insulating material is secured to the depending flange 12 by a fastening band 14, such as a clamping ring, a wrapping of cord, wire or the like, and the lower end of the shell 13 is fixed to the flange 15 of the insulator 6 by a similar band, cord or wire 15'. The shell 13 provides a substantially air-tight housing for the insulator 6 and prevents the deposit thereon of conductive material.

The shell or auxiliary insulator may be formed of any suitable insulating material, such as, for example, waxed or oiled paper, impregnated wood, cambric, glass or vitreous material, &c. The ends of the shell are, of course, at the same potentials as the adjacent ends of the insulators 6 and by analogy to the similar arrangement of electrical conductors, the insulators may be said to be "arranged in parallel". The auxiliary insulating surface will receive the deposits that otherwise would have formed on the insulator 6, and any leakage across the same will be indicated by a current flow greatly above that required for normal operation. When this condition exists the man-hole cover 10 is removed and the damaged insulating shell 13 is replaced. The operation is an exceedingly simple one, since no change or readjustment of the discharge electrode system is necessary.

The invention is particularly useful in connection with an electrical precipitator but may be applied to any insulators which are subject to damage arising from the deposition of conductive material.

As shown in Fig. 2, a pedestal type of insulator 16 is provided with an auxiliary insulating surface 17 which is secured to flanged disks 18 at the ends of the insulator by means of bands or wires 20. The upper disk 18 is provided with a depending flange 18' which is of larger diameter than the insulating surface 17 and protects the latter from any moisture or other condensate collecting upon the structure above the pedestal insulator.

As shown in Fig. 3, the invention may be applied to a strain insulator of the type made up from a plurality of unit insulators 21, the insulating surface 22 being fixed to disks 23 which are carried by the end units of the string of insulators.

As shown in Fig. 4, the insulator 24 is located within a drum or cylindrical container 25, which may be formed either of conductive or insulating material, depending upon the conditions encountered at the place of use of the insulator assembly. The upper end of

the insulator is provided with a flanged disk 26 and a sheet of insulating material 27 is fixed to the disk 26 and the upper portion of the drum 25 to form an air-tight closure for the drum.

If desired, the embodiment shown in Fig. 4 may be modified by omitting the sheet of insulating material 27 and completely filling the drum 25 with insulating material of a nature similar to or comprising gypsum, fine sand, kieselguhr or other siliceous material. This insulating material should extend to the top of the insulator and the top of drum 25. In this modification any conductive material in the zone of the insulator will deposit on or be absorbed by the filling material at its exposed top surface and will not affect the insulator. Consequently, any electrical leakage will be through the insulating material and not over the porcelain insulator surface. Should a break down occur, the insulation of the surface can be reestablished by renewing as much of the insulating material as may be found to be necessary.

In each of the embodiments which are illustrated in the drawings the auxiliary insulator or protective surface is of such form and composition that it may readily be replaced in less time and/or at less cost than the principal insulator. Because of the time which may be required to replace a damaged insulator it is quite possible that economy in operation could be effected even though the auxiliary insulating surface were more expensive than the principal insulator. For this reason the term "relatively inexpensive" as employed in this specification and the following claims is not used to identify auxiliary insulator constructions which are necessarily less expensive than the principal insulators which they protect. As a general rule, however, the auxiliary insulating surfaces will be provided by textile or other cellulosic materials which are much less expensive than the ceramic insulators which they protect.

The specific embodiments which have been described above are illustrative of the wide application of the invention and it is to be understood that material changes may be made in the several parts, their relative size, shape and arrangement without departure from my invention as set forth in the following claims.

I claim:

1. The combination with an insulator, disks arranged at the ends of said insulator, and a sheet of insulating material cooperating with said disks and spaced from said insulator to form a substantially air-tight housing for said insulator.
2. The combination with an electrical insulator, of a housing preventing the deposition of conductive material upon said insulator, the ends of said housing being secured to and

subjected to the electrical potentials at the respective ends of said insulator, and a portion of said housing being formed of relatively inexpensive insulating material spaced
5 from said insulator to provide a chamber surrounding the same.

3. In an electrical precipitator for removing tar and the like from gases, a treater chamber having discharge and collecting
10 electrode systems therein, an insulator compartment communicating with said chamber, an insulator within said compartment and providing a support for said discharge electrode system, and a second insulator sur-
15 rounding said supporting insulator and providing a substantially air-tight enclosure for the same, said second insulator being formed of relatively inexpensive material.

4. The combination with an electrical in-
20 sulator, of a substantially air-tight housing enclosing said insulator to prevent the deposition of conducting material thereon, said housing having portions thereof connected to and at the electrical potentials of the respective
25 ends of said insulator, and having another portion thereof formed of an insulating material having a low mechanical strength.

5. In an electrical precipitator; the combination with a discharge electrode, and an in-
30 sulator providing a support therefor, of a gas-tight housing enclosing said insulator, said housing comprising insulating material in parallel with the said insulator.

6. In an insulator, the combination with a
35 rigid body of insulating material having rigid connecting means at the respective ends thereof, of insulating material removably disposed around said rigid body and connected to the respective connecting means to provide
40 an air-tight enclosure for said rigid body and a non-conductive path in parallel to said rigid body.

7. In an insulator, a rigid body of insulating material, solid connecting means at both
45 ends thereof, and a flexible body of insulating material connected therebetween and forming an air-tight enclosure around said rigid body.

8. In an insulator, a rigid body of insulating material, solid connecting means at both ends thereof, and a removable body of insulating material connected therebetween and forming an air-tight chamber around said rigid body.

55 In testimony whereof, I affix my signature.
ROBERT B. HESSON.
